UNITED STATES PATENT OFFICE.

JAMES KELLY AND FREDERICK C. VOLKMAN, OF BALTIMORE, MARYLAND, ASSIGNEES
TO CITIES ILLUMINATING CO., OF NEW YORK, N. Y., A CORPORATION OF NEW
YORK.

GAS BURNER.

Application filed August 8, 1921. Serial No. 499,619.

To all whom it may concern:

Be it known that JAMES KELLY and FREDERICK C. VOLKMAN, citizens of the United States, residing at Baltimore city, in the 5 State of Maryland, have invented certain new and useful Improvements in Gas Burners, of which the following is a specification.

This invention relates to improvements in 10 gas burners for illuminating purposes, and more particularly to that class of burners for either street or house, in connection with which a mantle is used.

In burners of this class in common use 15 a pilot is employed that burns constantly with a low flame, but which is adapted when the main flow of gas is turned on, to project one or more tongues of flame against the mantles, the number of the flames depending upon the number of mantles employed 20 in different style burners. The most common one in use is a two mantle burner, consequently, the pilot is so arranged that the flames are projected in upward divergent 25 projections to light each of the oppositely disposed mantles.

One of the objects of this invention is to improve upon the pilot arrangement of these burners, and another object particularly 30 is to improve upon the flush arrangement of the ordinary burner, as well as to generally improve this class of burners in the particulars of ease of assembling and disassembling the parts for repairs, all as will appear from the following description.

In the drawings illustrating the invention,—

Fig. 1 is a front elevation of a burner constructed in accordance with our invention.

40 Fig. 2 is an edge elevation.

Fig. 3 is a central section of the upper portion of the burner.

Fig. 4 is a detail central section of the upper part of the burner taken upon a line 45 diametrically opposite that upon which Figure 3 is taken, and

Fig. 5 is an enlarged detail perspective view of the upper end of the flush tube showing the manner of flushing the upper 50 part of the burner in opposite directions with a "pre-charge," or a charge which reaches the burner nozzles slightly in advance of the main flow.

Referring to the drawings, the numeral 1 55 designates the pipe connected with the main,

which is threaded to receive a cap 2 integral with the valve case 3 in which works the valve 4 operated by the rocker arm 5. This valve case contains the various channels or by-passes controlled by the valve, 60 and these by-passes, it will be understood, lead to the main burner 2, and to the flush and pilot tubes, and since this invention does not reside in the construction of the valve case, its by-passes, channels, etc. they 65 need not, it is thought, be illustrated or described in further detail.

The numeral 6 designates the main burner tube which comprises a lower section 7, and an upper section 8, in which there is interposed the usual bunsen 9. The upper end of the upper section 9 is threaded as indicated at 10, for the reception of the downwardly extending internally threaded socket 11 of the tubular T-head 12. The down-turned portions 13 of the T-head are each provided with a flange 14, below which there are threads 15 which receive the upper ends of fittings 16, which are internally threaded as indicated at 17 to receive the 80 threaded ends of the nozzles 18. Interposed between the upper ends of the fittings 16 and the flanges 14, and preferably held steady by washers 19 are shade holders 20. Each holder is provided with an inwardly 85 extending ledge 21 cut through at intervals as indicated at 22 for the passage of ears formed upon the usual rings 23, which rings embrace the upper reduced part of the shades, and are held to the shades by the 90 usual thumb screws 24 passing through ears 25 on the rings, all of which is of common construction.

In the construction illustrated, the mantles are carried by the shade rings so that when 95 the shade rings are removed, the mantles are also removed. The manner of attachment of the shade to the shade holder is by inserting the shade and rings into the holders, and slightly turning them, the shade 100 rings being provided with laterally extending ears that rest upon the ledges 21 of the holders, which is also common.

The numeral 26 designates the pilot tube. This is let into the valve case and secured 105 thereto by a coupling 27, and its lower end communicates with the pilot passage in the case as is usual. The upper end of the pilot tube opens into a substantially spherical coupling 28, whose lateral extensions 29 are 110

threaded internally for the reception of laterally extending tubes 30, whose outward extending ends are bent downwardly and are provided with heads 31, which seat 5 upon upwardly extending members 32 externally threaded for the reception of couplings 33. The numeral 34 designates what may be called the pilot tube ends. These fit snugly into the members 32 and the holes in 10 these ends register with the holes in the laterally extending tubes 30, and each of the ends are further provided with tips 35 having very small perforations 35' therein, the tips constituting the pilot burners, and the 15 arrangement is such that the pilot flame will be maintained only when the main gas supply is turned off, and they are again ignited as the main burner flame goes out. Thus the pilots are what is known as "12 20 hour pilots," the gas issuing from the small perforations in the ends of the tips is under such pressure and its velocity is so great in proportion to the amount of gas which can escape through the perforations, that there 25 is enough air surrounding the tips to bunsenize the flame without the necessity of interposing in the pilot tube, a Bunsen device.

We have found by experiment by such an 30 arrangement of pilot that when the main flow of gas is turned on, the mantles come to a state of incandescence gradually without shock or explosion, thus completely eliminating the danger of rupturing the fragile 35 mantles, as is often the case where a yellow flame of considerable volume and force is projected with more or less violence directly against the mantles. Indeed, one of the primary purposes of this pilot is to obviate 40 the objection to the ordinary yellow flame pilot, which not only has a tendency to rupture the mantle, but where it is used in connection with more than one burner, sometimes fails to project flames of equal length, 45 in which cases only one of the mantles are lighted, due in many instances to stoppages of the small ducts, from which the yellow flames issue when the main gas supply is turned on.

The numeral 36 designates the flush tube, 50 the lower end of which is let into the valve casing 3, and the upper end of this tube is bent inwardly, and enters the central portion of the T-head 12, as shown more clearly 55 in Figure 4. The inner end of the tube is closed, and on opposite sides the tube is provided with small apertures 37, and these oppositely disposed apertures open in the direction of the flow of gas through the 60 T-head so as to project an equal amount of flushing gas to each of the nozzles. This flushing charge, it will be understood, enters the nozzles slightly in advance of the main flow so as to supply the burners proper 65 with a sufficient amount of gas to condition

the mantles to receive and take care of the main volume which follows.

It is customary in burners of this type to use in the nozzles 18 a spreader, which consists of a device supported by the nozzle, 70 and which partly fills its lower end, but by the use of the form of pilot illustrated and described, we are enabled to eliminate these spreaders since obviously the location of the tips 35 at the lower end of the nozzle will 75 act as a spreader for the main supply of gas, and causes it to issue from the nozzle in a circular film rather than in a volume commensurate with the interior diameter 80 of the nozzles.

It will be understood that the lower end of the flush tube registers with a suitable duct or by-pass in the valve case 3, which by-pass is controlled by the valve in such manner that as the valve is opened, the 85 flushing supply will pass into the flush tube in advance of the opening of the by-pass which controls the main supply.

It will be seen that the construction illustrated, or especially with regard to the 90 pilot arrangement is such that the parts can be very readily assembled and taken apart for cleaning or repairs.

While from the foregoing description, the operation of the burner will probably 95 be understood by those skilled in such matters, nevertheless a short statement of the operation will be made.

Assuming the pilot burner 35 to be lighted, and burning with a very small blue 100 flame, bunsenized for the reasons heretofore given, the rocker arm 5 is moved downwardly, and in its downward movement the valve will establish, momentarily, communications between the main and the flush 105 tube, supplying the flush tube, which supply will be projected in opposite direction to and through the two nozzles. A further movement of the valve will establish communication between the main and the burners 110 to maintain the mantles in the required and full state of incandescence.

A still further movement of the valve will cut off communication between the main and the pilots 35 extinguishing them. 115 A movement of the valve in the reverse direction to extinguish the lights will open the by-pass to the pilots which are again lighted from the dying products of combustion 120 from the mantles, the pilots continuing to burn until the main supply of the gas is again lighted.

We claim—

1. In a burner of the class described, in combination, a burner tube formed with a 125 horizontal portion at its upper end, and a nozzle communicating with said horizontal portion, a flush tube extending into said horizontal portion, said tube having a closed end and a laterally extending orifice adapt- 130

ed to project the flushing charge laterally through the horizontal portion of the burner tube to the nozzle.

2. In a gas burner of the inverted type, a burner tube and means for supplying gas to said tube, a head connected with said tube and having down-turned portions, an inverted nozzle attached at the end of each down-turned portion, a flush tube let into the head, said tube having a closed end and oppositely disposed aperture whereby a flush charge may be projected simultaneously in opposite directions to and through each of the downturned portions of the head.

3. In a gas burner of the inverted type, a burner tube and means for supplying gas to said tube, a head connected with said tube and having downturned portions, an inverted nozzle attached at the end of each downturned portion, a flush tube let into the head, said tube having a closed end and oppositely disposed aperture whereby a flush charge may be projected simultaneously in

opposite directions to and through each of the down-turned portions of the head, a pilot tube, pilot burners extending into each of the nozzles, means for establishing communication between the pilot tube and the burners, the said pilot burners being adapted to act as pilots to ignite the gas issuing from the nozzles, and as spreaders to properly distribute the gas as it issues from the nozzles.

4. In a gas burner, in combination with the main burner tube of a plurality of gas distributing tubes intersecting the burner tube, and a flush tube entering the distributing tubes at a point of intersection between the former and latter.

In testimony whereof we affix our signatures in presence of two witnesses.

JAMES KELLY.
